UNITED STATES PATENT OFFICE.

CHARLES M. RHODES, OF STEUBENVILLE, OHIO.

METALLIC TIE AND RAIL-FASTENER.

No. 834,682.

Specification of Letters Patent.

Patented Oct. 30, 1906.

Application filed June 18, 1906. Serial No. 322,176.

To all whom it may concern:

Be it known that I, CHARLES M. RHODES, a citizen of the United States of America, residing at Steubenville, in the county of Jefferson and State of Ohio, have invented certain new and useful Improvements in Metallic Ties and Rail-Fasteners, of which the following is a specification, reference being had therein to the accompanying drawings.

This invention relates to certain new and useful improvements in metallic ties and rail-fasteners; and the invention has for its object to provide a durable and inexpensive tie wherein positive and reliable means are employed for firmly retaining a rail upon said tie. To this end I have devised a tie that can be easily rolled, the tie being of such a shape as to eliminate any possibility of the same being laterally displaced when mounted in a well-ballasted road-bed. The tie constitutes a portion of the rail-fastener, the remainder of the fastener being detachable from the tie, whereby a worn or injured rail can be easily and quickly removed and replaced by a perfect rail.

The construction of the tie and rail-fastener will be hereinafter described in detail, illustrated, and specifically pointed out in the appended claims.

Reference now being had to the drawings forming part of this specification, Figure 1 is a perspective view of one end of my improved tie, illustrating a rail secured thereto by my fastener. Fig. 2 is a plan of the same. Fig. 3 is a perspective view of a rail-fastener. Fig. 4 is a similar view of a locking-yoke used in connection with the fastener. Fig. 5 is a plan of a portion of the tie. Fig. 6 is a bottom plan of a portion of the tie. Fig. 7 is a cross-sectional view of the tie, illustrating the detachable portion of my improved rail-fastener. Fig. 8 is a perspective view of a stirrup used in connection with the rail-fastener; and Fig. 9 is a bottom plan of a portion of a tie, illustrating a slightly-modified form of construction.

My improved tie constitutes a rolled T-shaped bar 1, the horizontal portion or top 2 of which is slightly curved, while the depending flange 3 is tapered. In some instances this flange can be undulating, as at 4, (see Fig. 9,) to take a more positive grip in the road-bed upon which it is placed.

The tie adjacent to each end is provided with a raised portion forming a seat 5 for a rail 6. The seat 5 upon each side of the

flange 3 is cut and sheared, as at 6^a, to form two lugs 7, which are bent to form fasteners for the base-flange 8 of the rail 6.

The seat 5 opposite the lugs 7 and upon each side of the flange 3 is provided with oblong openings 9, the under side of the top 2 at one side of each opening being beveled, as at 10, the object of which will presently appear.

Straddling the material between the openings 9 and the flange 3 is a stirrup 11, comprising a head 12, a neck portion 14, and depending hook-shaped legs 15. The legs 15 engage the outer edges 16 of the opening 9, and the head 12 serves a function which will presently appear.

In the curved portions 17 of the openings 9 are mounted fasteners 18, each fastener comprising an oval or eccentric shank 19, having arms 20 and 21 formed at right angles to 75 said shank. The underneath surface of the arms 22 is beveled, as at 22^a, to engage the base-flange 8 of the rail 6. The arms 21 are adapted to engage the beveled surfaces 10 at the sides of the openings 9.

To retain the fasteners 18 in engagement with the tie 1 and the rail 6, I use a locking-yoke 23, the edges of the jaws 24 of said yoke being formed with inner serrated edges 25 and outer tapering edges 26.

Before placing the rail 6 upon the top 2 of the tie the fasteners 18 are placed in the openings 9, said fasteners being turned whereby the arms of said fasteners will not interfere with the placing of the rail upon a tie. After 90 the rail has been properly positioned in engagement with the lugs 7 the fasteners 18 are rotated until the arms 22 engage the base-flange 8 of the rail 6, and then the stirrup 11 and the locking-yoke 23 are placed in position. 95

The locking-yoke is adapted to embrace the neck portion 14 of the stirrup beneath the head 12, the jaws 24 of said yoke passing between the stirrup and the fasteners 18. The beveled edges 26 of the yoke are adapted to force the 100 arms 22 of the fasteners outwardly into engagement with the base-flange of the rail 6.

The locking-yoke as it is driven inwardly toward the rail becomes fixed upon the stirrup 11 by the serrated edges 25 of the jaws 24 engaging the neck portion 14 of the stirrup. The disposition of the teeth or serrations of the jaws 24 prevents the locking-yoke from becoming disengaged from the stirrup, and when it is necessary to remove the rail 6 the 105 yoke is severed adjacent to the stirrup to permit of its removal in the direction of the rail 6.

When the locking-yoke is driven inwardly to partially rotate the fasteners 18, the oval or eccentric shank 19 of each fastener forces the base-flange 8 of the rail 6 toward the lugs 5 7 7, while the arms 21 of said fasteners firmly lock the base-flange 8 of the rail 6 upon the tie by virtue of the beveled surface 10, formed adjacent to the openings 9 9, upon the under face of the tie 1.

10 The fasteners, stirrup, and locking-yoke are constructed of strong and durable metal, the locking-yoke being preferably made from sheet-steel, whereby it may ride upon the base-flange 8 of the rail 6 when driven inwardly and may be easily severed at any time the rail 6 is to be removed.

15 What I claim, and desire to secure by Letters Patent, is—

1. In a metallic tie, and rail-fastener, the combination with a rail, of a T-shaped bar having its top raised to form a seat for said rail, lugs carried by said tie, and adapted to form fasteners at one side of said rail, eccentric fasteners movably mounted in the top of 25 said tie, and adapted to engage said rail, a stirrup detachably mounted in said tie, a locking-yoke embracing said stirrup and engaging said fasteners, and means to lock said yoke in engagement with said stirrup and 30 said fasteners, substantially as described.

2. In a metallic tie and rail-fastener, the combination with a rail, of a T-shaped bar adapted to support said rail, lugs carried by the top of said bar and forming fasteners at one 35 side of said rail, eccentric fasteners mounted in said bar and adapted to engage said rail, a

stirrup mounted between said fasteners, means embracing said stirrup to lock the last-named fasteners in engagement with said rail, and means to lock the last-named means in 40 engagement with said stirrup, substantially as described.

3. In a metallic tie and rail-fastener, the combination with a rail, of a T-shaped bar adapted to support said rail, fasteners carried 45 by said bar and adapted to engage one side of said rail, detachable fasteners carried by said bar and adapted to engage the other side of said rail, arms carried by the last-named fasteners and adapted to overlie the flange of 50 said rail, and means interposed between the last-named fasteners to lock said fasteners in engagement, with said rail, said means including a stirrup embraced by a locking-yoke, substantially as described.

4. In a metallic tie and rail-fastener, the combination with a rail, of a bar supporting said rail, fixed fasteners carried by said bar, and engaging one side of said rail, movable fasteners carried by said bar and engaging 60 the other side of said rail, a locking-yoke mounted between said movable fasteners and holding said fasteners in engagement with said rail, and means to hold said locking-yoke between said fasteners, substantially as de- 65 scribed.

In testimony whereof I affix my signature in the presence of two witnesses.

CHARLES M. RHODES.
